SANITARY APPLIANCE

Filed July 18, 1931

Inventor

HENRY PANULLO

By Clarence O'Brien
Attorney

UNITED STATES PATENT OFFICE

HENRY PANULLO, OF ATLANTIC CITY, NEW JERSEY

SANITARY APPLIANCE

Application filed July 18, 1931. Serial No. 551,742.

This invention relates to improvements in sanitary appliances and has particular reference to a sanitary pad holder for women and a suspensor for men.

5 The primary object of the invention resides in a sanitary appliance adapted to be worn about the waist of a wearer so as to securely and comfortably hold a sanitary pad in position when the appliance is used as a sanitary belt for women, and which will likewise support the genital sack of a male when worn as a suspensor.

10 Another object of the invention is to provide a surgical appliance of the above character which will adapt itself to the body of the wearer and permit of the natural body movement without shifting.

15 A further object is the provision of a sanitary appliance wherein the suspender straps which support the pad holder and sack from the waist encircling belt are freely passed about the front and back of the belt to reduce the strain upon the straps during body movement of the wearer.

20 With these and other objects in view, the invention resides in the certain novel construction, combination, and arrangement of parts, the essential features of which are hereinafter fully described, are particularly 25 pointed out in the appended claim, and are illustrated in the accompanying drawing, in which:

Figure 1 is a perspective view of my sanitary appliance in the form of a sanitary pad holder.

30 Figure 2 is a side elevational view of the same.

Figure 3 is a top plan view of the adjustable pad support.

35 Figure 4 is an enlarged vertical transverse sectional view on the line 4—4 of Figure 3.

Figure 5 is a modification showing the appliance adapted for use as a suspensor for men.

40 Referring to the drawing by reference characters, the numeral 10 designates an elastic belt or waist encircling band which may be constructed of elastic webbing and mounted exteriorly at the front and back of the belt are single loops 11, while disposed

55 adjacent the front and back sides of the belt are double loops 12. Slidable through the loop 11 at the front of the belt is a front elastic strap 13 which may be either flat or round, and which strap passes around the sides of the belt toward the rear of the same from where it is extended downwardly. This strap passes through one of the eyes of the double loop 12. Slidable through the loop 11 at the rear of the belt 10 is a back strap 14, the ends of which are brought forward around the sides of the belt and passed through the other eyes of the double loops 12. The terminal ends of the back strap extend downwardly and terminate adjacent the belt for a purpose to be presently described.

60 The construction thus far described is present in both forms of the invention, that is when the appliance is designed as a sanitary pad holder for women and a suspensor for men.

65 In Figures 1 to 4 inclusive, I have illustrated the belt and the front and back straps as being associated with a sanitary pad or napkin holder 15 which comprises a substantially triangular shaped member 16 of flexible water proof material. The member 16 is constructed of two thicknesses of material 17 and 18 as best seen in Figures 3 and 4 of the drawing, and which thicknesses are stitched along their side edges as at 19 and along the wider end edge 20. The stitching between the edges 19 and 20 terminates short of each other to provide open spaces for the free 70 sliding of a pair of suspended straps 21 which are also constructed of elastic material. The center of the member 16 is stitched as at 22 to prevent separation of the thicknesses of material and which stitching coacts with the other stitching to provide hems or passages for the free sliding of the member 16 upon the suspender straps 21. The straps 21 cross each other adjacent one end of the member 16 and the free ends of the said straps are 75 detachably connected to the terminal ends of the front and back straps 13 and 14 respectively. The terminal ends of the front and back straps are provided with buttons 23, while the terminal ends of the suspender straps are provided with button holes 24.

Slidable upon the suspender straps, are tubular fabric coverings 25 which protect the skin of the body of the wearer from becoming chaffed by reason of the direct contact of the elastic strap therewith.

From the form of my invention shown in Figures 1 to 4 inclusive, it will be seen that when the belt is applied to the waist of a woman wearer, a sanitary pad may be placed upon the pad holder or member 16 and the said member adjusted as to properly position the pad against the body of the wearer. When the appliance is in a worn position, and it is desired to change a pad, it is only necessary to unbutton the suspender straps at the front or rear, and for sanitary reasons the straps may be entirely unbuttoned from the belt straps and the lower harness washed. By mounting the front and back straps in loops provided on the belts, it will be seen that the front and back straps are capable of sliding around the belt whereby any strain upon the suspender strap is greatly reduced, and which strain may be caused by the natural body movement of the wearer.

In Figure 5 of the drawing, I have illustrated the same type of belt as that shown in the preceding form, but instead of providing a pad holder suspended from the belt, I provide a sack or pouch 26 to which the lower ends of suspender straps 27 are buttonable as at 28. The straps 27 are crossed directly above the pouch 26 and are buttonable to the front and back straps as at 29, or in the same manner as that previously described.

From the foregoing description, it will be seen that the principle of my invention may be adapted for the two-fold purpose of supporting a sanitary pad in position, upon a woman wearer, or the belt may support a suspensory sack for use by men. By reason

of the elasticity of the various straps and the loose connection between the straps and the belt, the appliance may be worn with comfort and with the feeling that the parts are properly supported.

70

While I have shown and described what I deem to be the most desirable embodiments of my invention, I wish it to be understood that various changes in construction may be resorted to as come within the scope of the appended claim.

75

Having thus described the invention, what I claim as new and desire to secure by Letters Patent is:—

An appliance of the class described comprising a waist encircling band, front and rear loop forming members attached to the upper part of said band each member forming a single loop, a pair of spaced double loop forming members at each side of the band, each of the last-mentioned loop-forming members providing an upper loop and a lower loop, a strap passing through the front single loop forming member and through the upper loops of the front members of the pairs of double loop forming members, and through the lower loops of the rear pair thereof with the ends of the strap curving downwardly, a second strap passing through the rear single loop forming member and through the upper loops of the rear members of the two pairs of double loop forming members and through the lower loops of the front members of the two pairs of members, with the ends of the second strap, curving downwardly, supporting straps having their upper ends detachably connected to the depending ends of the two first-mentioned straps, and a supporting member carried by the supporting straps.
